UNITED STATES PATENT OFFICE.

WALTER LANE, OF HOLLAND, MICHIGAN, ASSIGNOR TO BUSH & LANE PIANO COMPANY, A CORPORATION OF ILLINOIS.

DESIGN FOR A CABINET-PHONOGRAPH.

57,680.

Specification for Design.

Patented Apr. 26, 1921.

Application filed October 28, 1918. Serial No. 260,076. Term of patent 14 years.

To all whom it may concern:

Be it known that I, WALTER LANE, a citizen of the United States, residing at Holland, in the county of Ottawa and State of Michigan, have invented a new, original, and ornamental Design for a Cabinet-Phonograph, of which the following is a specification, reference being had to the accompanying drawing, forming a part thereof.

The figure is a perspective view of a cabinet phonograph showing my new design.

I claim—

The ornamental design for a cabinet phonograph, as shown.

WALTER LANE.
